UNITED STATES PATENT OFFICE.

EDWIN NORTON, OF PAGET WEST, BERMUDA, AND LOUIS C. KRUMMEL, OF BROOKLYN, NEW YORK; SAID KRUMMEL ASSIGNOR TO PERFECT VACUUM CANNING COMPANY, OF CHICAGO, ILLINOIS, A CORPORATION OF MAINE.

VACUUM SEALING APPARATUS.

1,264,844.

Specification of Letters Patent. Patented Apr. 30, 1918.

Application filed June 29, 1914. Serial No. 847,980.

To all whom it may concern:

Be it known that we, EDWIN NORTON and LOUIS C. KRUMMEL, citizens of the United States, residing at Cedar Lodge, Paget 5 West, Bermuda, and Brooklyn, in the county of Kings, State of New York, respectively, have invented certain new and useful Improvements in Vacuum Sealing Apparatus, of which the following is a description, reference being had to the accompanying drawing and to the figures of reference marked thereon.

The invention relates to new and useful improvements in machines for closing cans 15 or containers, and more particularly to machines wherein the air is exhausted from the container subsequent to the final sealing of the same.

An object of the invention is to provide 20 an apparatus or a machine of the above character, wherein the containers to be closed travel continuously during the exhausting of the air from the containers, and during the final sealing of the same.

25 A further object of the invention is to provide a machine for closing cans or containers wherein a continuously rotating support is provided with a plurality of closing stations traveling with the support, each of 30 which includes means for exhausting the air from the can or container, and means for closing the can or container while it is still connected with the vacuum creating means, which rotating support is also fed with the 35 cans or containers during the continuous travel thereof.

These and other objects will in part be obvious, and will in part be hereinafter more fully disclosed.

40 In the drawings, which show by way of illustration one embodiment of the invention,

Figure 1 is a view partly in section and partly in side elevation, showing an apparatus embodying our improvements.

Fig. 2 is an enlarged vertical section through the upper part of the apparatus.

Fig. 3 is a plan view showing the supporting table and the path of travel of the con-

tainers during the exhausting of the air and 50 the closing of the same.

Fig. 4 is a detail showing the upper end of the container in section and the sealing chamber in contact therewith.

Fig. 5 is a similar view, showing the aperture, in the container closed.

Fig. 6 is a detail showing the valve in one of the vacuum pipes.

Fig. 7 is a detail showing the tripping pin for the valve which controls the vacuum. 60

Fig. 8 is a vertical sectional view on an enlarged scale showing the upper part of the supporting post and the various devices supported thereby.

Fig. 9 is a horizontal sectional view 65 through the valve for controlling the vacuum.

The invention consists generally in providing an apparatus in which the containers to be closed are received by a continuously 70 traveling support, with which are associated separately operating sealing chambers and solder heating devices, so that the cans may be fed in succession on to the traveling support, and during the travel of the support, 75 the air is exhausted from each can or container, after which the aperture formed therein is closed by solder or otherwise.

The sealing chamber is so constructed as to engage the end only of the container and 80 surround the aperture through which the air is exhausted from the container. Said sealing chamber is provided at its lower end with a bell-shaped elastic member which engages directly the end or outer wall of the 85 container, so that the atmospheric pressure on said rubber wall will tend to form a tight joint between the same. Each sealing chamber is provided with a pipe leading to the vacuum chamber, and a valve in the pipe 90 is operated in timed relation to the travel of the support and container, so that the air is exhausted from the container after which a soldering iron melts the solder surrounding the aperture in the container, so as 95 to close the aperture, and after the aperture is closed and the solder cooled or set, the sealing chamber is withdrawn from con-

tact with the container; so it may be discharged from the traveling support.

The apparatus also includes devices whereby the pipe leading from the vacuum creating means to each vacuum chamber is held closed unless a can is presented to the closing device, and devices are also provided for releasing the vacuum in the vacuum chamber subsequent to the raising of the vacuum chamber from contact with the can or container.

Referring more in detail to the accompanying drawings, the invention consists in an apparatus for closing containers, which is preferably provided with a supporting base 1, from which rises a vertical post 2, around which a table or support 3 is rotated. This support 3 is carried by a sleeve 4, which surrounds the fixed post 2, and said sleeve 4 at its lower end carries a gear which meshes with a worm gear on the main shaft 5. The main shaft 5 may be driven by a suitable belt wheel 6. The rotation of the main shaft will cause the support 3 and the sleeve on which it is mounted to rotate about the central fixed post 2. This support 3 is preferably driven at a uniform speed and moves continuously. The containers 7 to be closed, are preferably of the type shown in detail in Figs. 4 and 5.

The cover 8 or upper end of the container is seamed on to the same in any desired way, and said cover has an aperture 9 through which the air may exhausted from the container. A protecting cap 10 is preferably secured to the under face of the cover, directly beneath the aperture 9, and this cap is formed with suitable openings, so as to permit the air to be exhausted through the aperture 9, but prevents any solid floating parts in the container from contacting with the aperture, so as to prevent a proper exhausting of the air.

Solder is preferably used for closing the container, and as shown in Fig. 4, the solder disk 11 is attached to the cover, and is perforated so that the aperture through the solder is in alignment with the aperture in the cover. It is obvious however that solder may be fed to the tipping iron instead of being applied to the cover of the can.

The containers to be closed are fed to the rotating support 3 in the present embodiment of the invention, by a rotating drum 12, which is provided with a spiral thread 13 projecting slightly above a support 14 on which the containers are placed, and along which support the containers are fed. This drum may be rotated by a sprocket chain connection 15 with the main shaft 5. The containers may be fed to the drum if desired, or placed on the support 14, and will be conveyed along the same in proper timed relation to the travel of the support 3, so they

may be forced on to the traveling support 65 by the thread on the drum.

The traveling support 3 is provided with suitable gages to properly locate the containers in spaced relation to one another thereon. The present apparatus is designed so that there are twelve independent sealing chambers and solder heating devices, each of which travels with the traveling support 3. The sleeve 4 on which the traveling support 3 is mounted, also carries a head 16, which has laterally projecting arms supporting a web 17. The web 17 carries a series of bearings 18 and 19.

The sealing chamber for each closing device is formed of a sleeve 20, which is journaled in the bearing 18. This sleeve 20 at its lower end is threaded to receive an open cage or head 21. A glass sleeve 22 rests against a washer at the lower end of the sleeve 20, and an elastic bell-shaped member 23 rests against the lower edge of said glass sleeve. The cage 21 has a flange 24, which engages the rubber or elastic member 23 and presses the same against the glass sleeve, and the glass sleeve in turn against the packing washer at the lower end of the sleeve 20. This cage 21, as herein shown, has two laterally projecting arms 25 and 26.

The sleeve 20 is formed with an opening 27, which receives a pipe 28, through which the air may be exhausted from the sealing chamber.

A rod 29 extends through the bearing 19, and also has a bearing in the sleeve 20. This rod 29 is fixed to a head 30, on which is splined a gear 31. The gear 31 meshes with a non-rotating gear wheel 32, adjustably attached to the central post 2 of the apparatus. A set screw 33, and feather, may be used for this purpose. The head 30 carries a roller 34, which runs in a groove 35 in a cam ring 36, which cam ring is also rigidly fixed to the gear wheel 32. The roller 34 is carried by a collar 37, which is mounted on the head 30, and this permits the head to rotate freely in the collar as the gear 31 rolls about the stationary gear wheel 32.

The hub 16 rotates with the traveling table and this causes the bearings 18 and 19 to travel, and the sealing chamber and rod 29 will travel with said hub and bearings. As the head 30 is moved relative to the fixed cam ring 36, the roller 34 will travel along the cam groove in said ring. This groove is so proportioned as to raise and lower the rod 29.

A collar 38 is fixed to the rod 29, and a spring 39 is interposed between said fixed collar and a screw cap 40 threaded into the upper end of the sleeve 20. The rod 29 is formed with an enlarged section 41, which is located in the sealing chamber, and the upper end of said enlarged section is adapted

to engage the upper wall of the sleeve 20, and when the rod 29 is raised, said sleeve 20 will be raised therewith. When the rod 29 is depressed, however, the sleeve 20 will move downward therewith until the arms 26 engage the top of the container, which will limit the downward movement of the sleeve and permit the rod to have a further downward movement compressing the spring 39.

10 When the cage 21 rests on the upper end of the container, the elastic member 23 will be forced against the upper end of the container, as clearly shown in Figs. 4 and 5. This rubber section, as above noted, is bell-shaped, and is provided with a thin edge. The atmospheric pressure on the outer face of this rubber member when the air is exhausted from the sealing chamber, assists in forcing said thin edge of the rubber member 15 against the container top, and forms a tight sealing joint.

20

The rod 29 at its lower end is formed with a tipping iron 42. This tipping iron is electrically heated, and is so positioned relative 25 to the container that when it is moved downward by the cam roller 35, it will contact with the solder surrounding the aperture, and melt the same, causing the aperture to be closed, as clearly shown in Fig. 5.

30 The tipping iron 42 is electrically heated. One of the wires 43 leading to the tipping iron is connected to the metal work of the machine or apparatus for the return line of the current; while the other wire 44 leads 35 upward through the head and is connected to a terminal 45, which in turn is connected to a collar 46. This collar 46 is mounted on a sleeve 47 of insulating material. A second collar 48 also mounted on said sleeve 40 contacts with the first collar 46. This second collar 48 is attached to a rod 49, and the current for heating the tipping iron is supplied through this rod. This connection permits the head with the tipping rod to 45 be rotated. The sleeve 20 forming the sealing chamber does not rotate with the tipping rod, but moves up and down in timed relation to the reciprocations of the tipping rod.

50 At the upper end of the post 2 is a sleeve 50. This sleeve is threaded onto the post. A collar 51, having a cone face is seated against the lower face of the sleeve 50 and a suitable packing is placed between these 55 parts in order to make a tight joint. A ring 52, which is also cone shaped, seats against the collar 51 and this ring at its lower side rests on a collar 53, which is seated on the shoulder at the upper end of the post. The 60 ring 52 turns freely on the post and is provided with 12 openings. A pipe 54 is threaded into each opening and extends radially from the post, and overhangs the cam disk carried by the gear wheel 32.

The outer end of the pipe 54 is connected 65 by a pipe 55 to the pipe 28. This pipe 55 has a flexible section 55^a. The center of the post is formed with a chamber 2^a, and each of the openings in the ring is connected to this chamber 2^a by means of a port 2^b. 70 The vacuum chamber 2^a in the post is connected through a suitable pipe 56, shown in dotted lines in Fig. 1, to a pump. Each pipe 54 is provided with a valve 57. This valve is shown in detail in Figs. 6 and 9. 75 Said valve is cone-shaped, and is held seated by a spring 58. The valve is turned by a double lever 59. Mounted on the fixed cam ring is an adjustable pin 60 which is positioned so as to engage the double lever or 80 member 59 and open the valve. Another similar pin is mounted on said cam ring and positioned so as to close the valve. The valve casing 57 is also provided with an outlet port 57^a which leads to the atmosphere. 85 The cone valve rotating in the casing is a three way valve, having ports a, b and c. When the valve is in the position shown in Fig. 9, the vacuum chamber is connected with the vacuum apparatus so that the can or container will be placed under vacuum. 90 When the pin for closing the valve strikes the double lever 59, it will swing the cone valve so as to bring the port c into alignment with the port 57^a leading to the atmosphere, and this closes the pipe 54 leading to the vacuum pump, but opens the pipe 54 leading to the vacuum chamber as the port b is in register with this pipe. The timing of the operation of the valve is such 95 that the vacuum chamber is open to the atmosphere prior to the raising of the head so as to move the chamber out of contact with the can or container.

A tube 61 is threaded into the upper end 100 of the post and connects with the chamber formed in said post. A fiber disk 62 is mounted on said tube. A metal disk 63 rests on the fiber disk, and is insulated from the tube by a sleeve 64 of insulating material. A 105 second metal disk 65 rests on the disk 63, and a fiber disk 66 is clamped against the metal disk 65 by a nut 67.

The rods 49 are threaded into the metal disk 63 and this metal disk turns with the 110 hub and the combined sealing and closing devices. The metal disk 65 is held from turning, and is connected to a suitable source of electricity. A vacuum gage 68 is threaded on to tube 16, and closes the outer end of 115 the same.

In order to control the vacuum chamber so that when there is no can the vacuum pipe will not be open to the atmosphere, the pipe 28 is connected with a sleeve 69 which contains a valve operated by an arm 70. This arm 70 is pivotally connected with a rod 71 which slides in a bracket 72. The rod ex-

tends through the cage and a coil spring 73, bearing at one end against the bracket 72 and at the other end against a collar on the rod normally forces the rod downward. 5 When the head descends on to the can body, the rod projects below the cage so as to strike the can body and be raised before the cage engages the can body. This raising of the rod turns the valve in the pipe 55 so 10 as to open the pipe and permit free access between the vacuum chamber and the vacuum creating device when the valve 57 is opened. The lifting of the head will permit the spring 75 to move the rod downward and close this valve so that if no can 15 is placed underneath the head the vacuum pipe 55 will not be open to the atmosphere, even though the valve 57 be turned by the rotation of the support so as to connect the 20 pipe 55 through the pipe 54 with the vacuum creating means.

The operation of the apparatus will be apparent from the above description. The filled containers are fed by the drum on to 25 the rotating table. As the table rotates, the cam groove in the fixed cam ring will force the roller 34 downward, and this will lower the sleeve 20 and carry the cage into contact with the upper edge of the container, and at the same time carry the flexible rubber ring into contact with the cover 30 about the central aperture therein. By the devices above described, if there is a can underneath the head, then the vacuum chamber contained in the head will be connected 35 with the pipe 55 so that the can may be placed under vacuum. As the table continues to rotate, the valve-operating lever 50 comes into contact with the pin 60, which opens the pipe and allows the air to be exhausted from the container. After the air is fully exhausted from the container, a further downward movement of the rod 29 carries the tipping iron into contact with 45 the solder surrounding the aperture in the container, and said solder will be melted and caused to close the aperture. The sleeve 20 is maintained under a vacuum until the 50 solder is cooled or set, after which it is raised by the upward movement of the tipping iron.

Before the vacuum head is raised, the valve 57 strikes the second pin above referred to which closes the pipe between the 55 valve and the suction creating means and opens the pipe 28 through the valve to the atmosphere. It will thus be seen that the apparatus includes devices which exhaust the air from the container during the continued travel of the same, and also includes devices for closing the aperture in the container subsequent to the releasing of the container from the vacuum pressure.

The gear wheel 32 is of sufficient width

to permit the gear wheel 31 to reciprocate 65 with the tipping iron and still maintain its driving connection with said fixed gear. The hub 16, together with the fixed gear and fixed cam ring, are capable of being vertically adjusted on the supporting 70 column therefor, by shifting the position of the collar 69, which is threaded on the sleeve and is held in adjusted position by a set screw 70.

It is obvious that minor changes in the 75 details of construction may be made, without departing from the spirit of the invention, as set forth in the appended claims.

Having thus described our invention, what we claim is:

1. A vacuum sealing apparatus comprising a continuously traveling support for receiving apertured containers, means for feeding said apertured containers onto said support during the travel thereof, and 85 means associated with and moving with said traveling support for exhausting the air from said containers and for closing the apertures therein, said last-named means including a closing head having a vacuum 90 chamber, said head being adapted to engage the end of the container about said aperture, devices for placing the vacuum chamber under vacuum and whereby said vacuum chamber may be opened to the atmosphere 95 prior to the moving of the vacuum chamber out of contact with the end of the container, and a tipping iron located in said vacuum chamber.

2. A vacuum sealing apparatus comprising a continuously traveling support for receiving apertured containers, means for feeding said apertured containers onto said support during the travel thereof, means moving with said traveling support for exhausting the air from said containers and for closing the apertures therein, said means including a closing head having a vacuum chamber, means for moving said head into contact with the end of the container about its aperture, exhausting the air from the container and withdrawing the same from contact with the container during a single rotation of said support, a tipping iron for sealing the containers, 110 means for heating said iron, and means for moving said tipping iron into and out of contact with the aperture in the container after the air has been exhausted from the container and prior to the opening of the 115 vacuum chamber to the atmosphere.

3. A vacuum sealing apparatus comprising a continuously traveling support for receiving apertured containers, means for feeding said apertured containers onto said 125 support during the travel thereof, means moving with said traveling support for exhausting the air from said containers and

- for closing the apertures therein, said means including a closing head having a vacuum chamber, means for moving said head into contact with the end of the container and 5 withdrawing the same from contact with the container during a single rotation of said support, a tipping iron, means for heating the tipping iron, means for rotating the tipping iron, and means for moving the tipping iron into and out of contact with the 10 aperture in the container.
4. A vacuum sealing apparatus comprising a supporting base, a fixed post carried thereby, a sleeve rotating about said post, a 15 table carried by said sleeve, a hub fixed to said sleeve and carrying a support, a plurality of combined sealing and closing devices mounted on and moving with said support, each of said devices including a 20 sleeve movable up and down relative to the support, said sleeve having a chamber therein, and a member at its lower end adapted to engage a container about a central aperture therein, a pipe connected with the chamber in said sleeve for exhausting the air therefrom, a valve in said pipe, and means for automatically operating said valve during the travel of the hub for opening and closing said valve.
5. A vacuum sealing apparatus comprising a supporting base, a fixed post carried thereby, a sleeve rotating about said post, a table carried by said sleeve, a hub fixed to said sleeve and carrying a support, a 35 plurality of combined sealing and closing devices mounted on and moving with said support, each of said devices including a sleeve movable up and down relative to the support, said sleeve having a chamber therein, and a member at its lower end adapted to 40 engage a container about a central aperture therein, a pipe connected with the chamber in said sleeve for exhausting the air therefrom, a valve in said pipe, means for automatically operating said valve during the travel of the hub for opening and closing said valve, a tipping iron extending into said 45 sleeve for closing the aperture in said container, and means for heating said iron.
6. A vacuum sealing apparatus comprising a supporting base, a fixed post carried thereby, a sleeve rotating about said post, a table carried by said sleeve, a hub fixed to 50 said sleeve and carrying a support, a plurality of combined sealing and closing de-
- vices mounted on and moving with said support, each of said devices including a sleeve movable up and down relative to the support, said sleeve having a chamber therein, and a member at its lower end adapted 60 to engage a container about a central aperture therein, a pipe connected with the chamber in said sleeve for exhausting the air therefrom, a valve in said pipe, means for automatically operating said valve during 65 the travel of the hub for opening and closing said valve, a tipping iron extending into said sleeve for closing the aperture in said container, and means for heating said iron, a fixed cam, a head connected to said iron 70 and having a roller engaging said cam for reciprocating said iron, said iron having means for positively raising the sleeve and for yieldingly depressing the same.
7. A vacuum sealing apparatus comprising a supporting base, a fixed post carried thereby, a sleeve rotating about said post, a table carried by said sleeve, a hub fixed to 75 said sleeve and carrying a support, a plurality of combined sealing and closing devices mounted on and moving with said support, each of said devices including a sleeve movable up and down relative to the support, said sleeve having a chamber therein, and a member at its lower end adapted 80 to engage a container about a central aperture therein, a pipe connected with the chamber in said sleeve for exhausting the air therefrom, a valve in said pipe, means for automatically operating said valve during 85 the travel of the hub for opening and closing said valve, a tipping iron extending into said sleeve for closing the aperture in said container, means for heating said iron, a fixed cam, a head connected to said iron 90 and having a roller engaging said cam for reciprocating said iron, said iron having means for positively raising the sleeve and for yieldingly depressing the same, and means for rotating said iron.

In testimony whereof, we affix our signatures in the presence of two witnesses.
